Primary Examiner — Sandra Snapp*Assistant Examiner* — Holly E Thurman(74) *Attorney, Agent, or Firm* — Michael D. Paul; Gunn, Lee & Cave, P.C.(57) **CLAIM**

The ornamental design for a portable electronics case, as shown and described.

DESCRIPTION

FIG. 1 is a front view of a portable electronics case showing my design. The rear view is a mirror image of the front view. FIG. 2 is a left side view thereof, the right side view being a mirror image.

FIG. 3 is a top view thereof, the bottom view being a mirror image; and,

FIG. 4 is a front isometric view thereof.
The broken lines represent boundaries of the claimed design that form no part of the claimed design.**1 Claim, 2 Drawing Sheets***FIG. 1*

FIG. 2

FIG. 3

FIG. 4
